UNITED STATES PATENT OFFICE.

HARRY L. DARRAH, OF CHATHAM, NEW JERSEY, ASSIGNOR TO WESTERN ELECTRIC COMPANY, INCORPORATED, OF NEW YORK, N. Y., A CORPORATION OF NEW YORK.

SERVICE-OBSERVING SYSTEM.

1,194,721.

Specification of Letters Patent. Patented Aug. 15, 1916.

Application filed November 26, 1915. Serial No. 63,480.

To all whom it may concern:

Be it known that I, HARRY L. DARRAH, a citizen of the United States, residing at Chatham, in the county of Morris and State 5 of New Jersey, have invented certain new and useful Improvements in Service-Observing Systems, of which the following is a full, clear, concise, and exact description.

This invention relates to service observing systems for observing the character of service rendered upon telephone lines by the operating force of telephone exchanges and more particularly to such systems in which the service upon any one of a plurality of telephone lines may be observed 15 from a central point.

The object of this invention is to provide improved signaling means for such a system by means of which the number of the 20 telephone line, upon which the service is being observed, may be indicated to the observer.

In accordance with this invention, there is provided a trunk circuit extending from a 25 central office to a central point, and there terminating in a service observing desk. At the central office end of the trunk circuit, there is provided apparatus by means of which any one of a plurality of telephone 30 lines, to which the trunk circuit has access and upon which a call is made, may connect the particular telephone line to the trunk circuit and cause the operation of a signaling device at the other end of the trunk 35 circuit to furnish a signal to the observer stationed thereat, indicating that a call has been made and that the telephone has been connected to the trunk circuit. Apparatus associated with the trunk circuit, control 40 signaling devices at the service observing desk, which operate to furnish signals to the observer to indicate when a regular operator answers the call by plugging in on the calling line, when the regular operator collects 45 or refunds a coin on a telephone line equipped with coin collectors, and when the regular operator registers a call for a telephone line equipped with message registers, and to indicate the position of the switchhook at the station of the telephone line 50 upon which the call has been made. There is also provided apparatus, associated with the trunk circuit, which is controlled by the telephone line upon which a call has been

made and by the observer for controlling 55 the operation of signaling devices at the service observing desk, corresponding to the telephone lines to which the trunk circuit has access, whereby signals are furnished the observer to indicate the number of the 60 telephone line on which service is being observed.

This invention will be more fully understood by reference to the accompanying drawings illustrating one embodiment 65 thereof.

To obtain a clear idea of the entire system, Figures 1, 2, 3, 5 and 6 of the drawings should be arranged in the order shown in Fig. 7.

As shown in the drawings, this invention comprises a service observing trunk D of four wires extending between central offices X and Y. At the central office X, a plurality of telephone lines terminate, two of 75 which are shown in Fig. 1. In Fig. 1 is also shown an ordinary cord circuit E for interconnecting the telephone lines for conversation. In Fig. 2 there is shown the end of the service observing trunk D, which terminates in central office X. As shown in Fig. 5, the end of the service observing trunk D at central office Y terminates in a plurality of positions of a service observing 80 desk, the portion between the dotted lines 85 being one position F and that to the right being another position G. There may be other positions, but, for convenience, only the two are shown. Associated with the service observing trunk D is apparatus for 90 indicating to the operators at the service observing desk the number of the line upon which service is being observed. The indicating apparatus, which is located on the service observing desk, is shown in Fig. 6. 95

The service observing system embodying this invention is capable of use for observing the service upon any one of at least twenty-six telephone lines. For convenience, however, only the first and last telephone lines, #1 and #26, are shown in the drawings. Telephone line #1 is equipped at the substation with a coin collector, while telephone line #26 is equipped at the central office with a message register 32. Each 100 of these lines is connected to a pair of jacks by means of cords and plugs of four conductors. Telephone line #1 is connected to

70

80

85

90

95

100

125

jacks 139 and 140 by means of a cord 23 and plugs 24 and 25, and telephone line #26 to jacks 141 and 142 by means of a cord 26 and plugs 27 and 28. Associated with the service observing trunk D at central office X are three relays, individual to each telephone line, to which the service observing trunk D has access for connecting the trunk to the telephone line upon which a call is being made. Relays 109, 113 and 114 are individual to telephone line #1, and relays 110, 116 and 143 are individual to telephone line #26. The leads from jack 139 terminate in normally open contacts of relay 113, the lead from the upper contact of jack 140 terminates in a normally open contact of relay 114, and the lead from the lower contact of jack 140 extends through resistance 151 and the winding of relay 101 to battery; the leads from jacks 141 and 142 are similarly associated with relays 143, 116 and 101, resistance 152 and battery. For each pair of relays 113 and 114, and 143 and 116, shown in Fig. 2, there are three leads, A, B and C. For each pair of similar relays, individual to the remaining twenty-four telephone lines not shown, there would also be leads A, B and C. The three leads A, B and C for the various twenty-six pairs of relays are to be connected to the leads 1 to 7 inclusive, shown in Fig. 3, in the manner indicated in the table of Fig. 4. At the service observing desk, there is a lamp corresponding to each of the twenty-six telephone lines to which the service observing trunk D has access. For convenience, these indicating lamps are given numbers, 301 to 326, corresponding to the number of lines, 1 to 26. Relays 144, 145, 146 and 115 and resistances 147, 148, 149, 150, 165 and 166 are for the purpose of controlling the signal lamps on the service observing desk, which indicate to the operators thereat the number of the line connected to the service observing trunk D. At each operator's position of the service observing desk, there is an indicating key controlling the indicating apparatus. Key 217 in position F and key 218 in position G are for this purpose. Key 206 in position F and key 214 in position G serve to connect the position apparatus with the service observing trunk D and the telephone line connected with it, while key 219 in position F and key 220 in position G are for the purpose of releasing the service observing trunk from a connected telephone line.

The subscriber of telephone line #1, initiating a call, removes the receiver from the switchhook and deposits a coin 29 in the coin-box. Line relay 15 thereupon operates over a circuit from battery, through the winding of line relay 15, contact of cut-off relay 17, tip side of line, windings of electromagnet 30 of the coin-box and coin 29 to ground. The armature 31 of electromagnet 30 is unaffected by the establishment of this circuit. The operation of line relay 15 lights line lamp 16 and causes the operation of relay 101 over a circuit from battery, through the winding of relay 101, resistance 151, lower engaging contacts of the jack 140 and plug 25, and contact of line relay 15, to ground. The operation of relay 101 causes the operation of relay 102 over a circuit from battery, through the winding of relay 102, lower normal contact of relay 104, contact of relay 101, and normal contact of relay 105 to ground. The operation of relay 102 causes the operation of relay 201 over a circuit from battery, through the winding of relay 201, normal upper contact of relay 202, retard coil 203, tip conductor of service observing trunk, retard coil 106, normal upper contact of relay 108, and lower contact of relay 102 to ground. Relay 201, in operating, causes the lighting of lamp 204 in position F and lamp 205 in position G of the service observing desk, to indicate that a call is being made on one of the telephone lines to which the service observing trunk has access. The circuit for these lamps may be traced from battery through the contact of relay 201, the lower normally closed contacts of keys 206 and 214, and the lamps 204 and 205 in parallel to ground. The operation of relay 102 also causes the operation of relays 109 and 110 over a circuit from battery, through the windings of relays 110 and 109, upper contact of relay 102 and normal contact of relay 112 to ground. Relay 109, in operating, causes the operation of relays 113 and 114, relay 113 operating over a circuit from battery through the winding of relay 113, contact of relay 109, lower engaged contacts of jack 140 and plug 25, and the contact of line relay 15 to ground, and relay 114 operating over a circuit from battery through the windings of relays 115 and 114, contact of relay 109, lower engaged contacts of jack 140 and plug 25, and the contact of line relay 15 to ground. The operation of relay 113 connects the limbs of telephone line #1 to the tip and ring conductors of the service observing trunk. The operation of relay 114 causes the operation of relay 112 over a circuit from battery through the winding of relay 112, upper contact of relay 114, lower engaged contacts of jack 140 and plug 25, and the contact of line relay 15 to ground. The operation of relay 112 causes the release of relays 109 and 110. Relays 113 and 114, upon operating, are locked up over portions of the circuits just traced through the windings of these two relays to the lower contact of relay 114, then through the normal contact of relay 116, winding of relay 105 and upper normal contact of relay 104 to ground. Relay 105 operates, causing the release of relay 102, 130

and as long as relay 105 is operated, all other telephone lines, to which this service observing trunk has access, are prevented from being connected thereto, because the energizing circuit of relay 102 is open at the lower normal contact of relay 105. The release of relay 102 does not cause lamps 204 and 205 to be extinguished, for the operation of relay 112, already referred to, has furnished ground for maintaining relay 201 operated. Assuming that the lighted condition of lamp 204 is observed by the observer at position F of the service observing desk, this observer actuates key 206, thereby causing lamps 204 and 205 to be extinguished, and also causes lamp 207 to be lighted. Signal lamp 207 is responsive to the position of the connected subscriber's switchhook, as will be more fully explained later. The operation of this key 206 also connects the observer's telephone 221 to the service observing trunk D. When the regular operator, upon noticing the lighted condition of line lamp 16, answers by inserting the answering plug of the cord circuit E into the jack associated with telephone line #1, cut-off relay 17 and relay 117 operate over a circuit from battery through lamp 18, resistance 19, sleeve of the answering plug and jack to point 20, where it branches, one branch going through the winding of cut-off relay 17 and the other through the middle contact of relay 114, and the windings of relays 117 and 118, to ground. Relay 118 is marginal and does not now operate. The operation of the cut-off relay releases line relay 15, extinguishing line lamp 16, and releases relay 112. The operation of relay 117 causes relays 119 and 120 to operate in parallel over a circuit from battery through the contact of relay 117, normal contact of relay 121, upper normal contact of relay 119, windings of relays 119 and 120 in parallel, and upper normal contact of relay 104 to ground. The operation of relay 120 extends the tip and ring conductors of the service observing trunk, to which are connected the limbs of telephone line #1, through to position F of the service observing desk. The operation of relay 117 also causes the operation of relay 122 over a circuit from battery, through the contact of relay 117 and the winding of relay 122, to ground.

The operation of relay 122 causes the operation of relay 208 over a circuit from battery, through the winding of relay 208, lower normal contact of relay 202, retard coil 209, ring conductor of the service observing trunk, retard coil 124, middle normal contact of relay 108, and middle contact of relay 122 to ground. Relay 208, in operating causes the lighting of lamp 210, which indicates to the observer that the regular operator has answered the call. The circuit of lamp 210 is from battery, through

the contact of relay 208, contact 211 of key 206 and lamp 210 to ground. The operation of relay 122 also connects battery through its lower contact to a voltmeter relay 126, shown within the dotted lines in Fig. 3, 70 and completes Wheatstone bridge circuit in which resistance 127 forms the first arm, resistance 128 the second arm, resistance 21 and lamp 18 in parallel and in series with resistance 19 forming a third arm, and the 75 winding of cut-off relay 17, the windings of relays 117 and 118 in series, resistance 129 and resistance 130 in parallel, forming a fourth arm. A moving coil 131 is connected across this bridge from the junction of the 80 first and second arms to the junction of the third and fourth arms. The bridge in this condition is unbalanced, causing coil 131 to move to close contact 132, which short-circuits condenser 133 and resistance 134, 85 whereupon relay 135 operates over a circuit from battery through resistance 136, contact 132 of the voltmeter relay 126 and the winding of relay 135 to ground. The operation of relay 135 furnishes ground for 90 relay 201 in place of the ground which was removed therefrom by the release of relay 112, whereby lamp 207 remains lighted to indicate to the observer that the subscriber has the receiver off the switchhook. When 95 the subscriber restores the receiver to the switchhook, supervisory relay 22 releases, removing resistance 21 from parallel relation to lamp 18, thereby changing the resistance of the third arm of the bridge to such an 100 extent that the bridge becomes balanced. The coil 131 then assumes its normal position, opening contact 132, which releases relay 135. Relay 201 thereupon releases, extinguishing lamp 207, thereby indicating to 105 the observer that the subscriber has restored the receiver to the switchhook.

Assuming now that when lamps 204 and 205 are lighted, due to a call having been made on telephone line #1, neither key 206 or any of the other similar keys at the service observing desk was actuated. The operation of relay 105, hereinbefore referred to, would cause the operation of relays 121 and 122 over a circuit from battery, through the 110 winding of relay 212, contact 213 of key 214, contact 215 of key 206, lower normal contact of relay 216, winding of relay 121, lower normal contact of relay 119, winding of relay 128, normal contact thereof and alternate contact of relay 105 to ground. Relay 128 is marginal and does not now operate. The establishment of this circuit has the following important functions, as will more fully appear later: (1) 115 makes it possible for the service observing trunk to be released automatically by a regular operator when plugging in to answer, provided the observer has not taken up the call; (2) provides a guard signal to 120 (3) 125

- warn the observer in case the position apparatus at the service observing desk has been disconnected from the trunk circuit without releasing the trunk circuit, and (3) furnishes 5 a guard signal to the observer in case the subscriber takes the receiver off the switchhook, thus connecting and locking the telephone line to the service observing trunk, and then restores the receiver to the switchhook before the regular operator answers 10 by plugging in. This guard signal notifies the observer that the trunk circuit should be released.
- Relay 212 in operating, causes lamp 239 in 15 position F and lamp 240 in position G to be lighted. Lamps 204 and 205 are also lighted, due to the operated condition of relays 112 and 201. The lighted condition of lamps 204 and 239 and lamps 205 and 240 20 in positions F and G respectively, notifies the observers that the telephone line, on which a call has been made, has been locked onto the service observing trunk. If the key 206 at the service observing desk is actuated 25 before the regular operator plugs in to answer, relays 121 and 212 will be released so that upon the subsequent plugging in by the regular operator, lamp 210 will be lighted to apprise the observer of this fact.
- 30 If the regular operator plugs in to answer before the observer takes up the call (by actuating key 206), the operated condition of relay 121 permits the service observing trunk to be released, and relay 117 will operate, causing the operation of relay 104 over 35 a circuit from battery through the contact of relay 117, alternate contact of relay 121 and upper winding of relay 104 to ground. Relay 104 in operating, releases relays 105, 40 113, 114 and 115, thereby disconnecting the service observing trunk from telephone line #1 upon which a call was made. All apparatus associated with the service observing trunk thereupon returns to normal condition, ready to connect the service observing trunk to another of the telephone lines to which the trunk has access when a call 45 is made. Function #1 of the circuit through relays 121 and 212 is thereby accomplished.

With reference to function #2 above referred to, if the observer, after completing an observation on telephone line #1, disconnects the position apparatus by restoring 55 key 206 to normal position without releasing the trunk circuit by actuating release key 219, lamps 239 and 240 will be lighted to warn the observer that the trunk circuit has not been released.

60 As to function #3 of the circuit, including relays 121 and 212, the making of a call on telephone line #1 causes the lighting of lamps 204 and 205 and locks the telephone line to the service observing trunk (as hereinbefore explained), but if the subscriber on

telephone line #1 restores the receiver to the switchhook before the regular operator answers by plugging in and before the observer takes up the call, relay 112 will release, causing the lamps 204 and 205 to be 70 extinguished. Lamps 239 and 240 will remain lighted to notify the observers that the service observing trunk should be released.

Upon connection being completed between 75 the calling telephone line #1 and the called telephone line, the regular operator by actuating coin collect key 33 causes the coin 29 to be deposited in a proper receptacle. This is accomplished in this manner,—actuation 80 of key 33 causes the energization of electromagnet 30 over a circuit from negative battery 34, through winding of relay 36, upper alternate contact of key 33, tip contacts of the plug and jack, winding of electromagnet 85 30 and coin 29 to ground. Upon the energization of electromagnet 30, armature 31 is moved about its pivot point to close its lower contact and in so doing causes the deposit of the coin 29 into a suitable receptacle 90 in any well-known manner. The closure of the lower contact locks up the electromagnet 30 as long as key 33 remains actuated. The closure of the circuit from negative battery 34 operates relay 36 to cause the lighting of 95 pilot signal 37. Negative battery 34 and positive battery 38 are of higher voltage than the common battery at the central office, being preferably of 110 volts, while the voltage of the ordinary central office battery is 100 preferably 24. The actuation of key 33 also causes the operation of relay 155 over a circuit from negative battery 34 through the winding of relay 36, upper alternate contact of key 33, tip contacts of the plug and jack, 105 upper engaged contacts of the plug 24 and jack 139, upper contacts of relays 113, 120 and 122, winding of relay 155 and normal contact thereof to ground. The operation of relay 155 removes the short circuit from 110 about polarized relays 156 and 153, whereupon polarized relay 153 operates. Polarized relay 153 operates on negative battery from 34, but does not operate on positive battery from 38, while polarized relay 156 115 operates on positive battery from 38 but does not operate on negative battery from 34. Relay 155 in operating also causes the operation of relay 157 over a circuit from battery through the winding of relay 157 and the 120 alternate contact of relay 155 to ground. The operation of polarized relay 153 and relay 157 completes a circuit from battery, through interrupter 158, a condenser, contact of polarized relay 153, alternate contact 125 of relay 157, primary of repeating coil 159 and normal contact of relay 160 to ground. An interrupted flow of current in this circuit causes in the secondary of repeating coil 159 an induced flow of current, which 130

traverses the primary winding of repeating coil 222, whereupon current will be induced in the secondary thereof. The path of the induced flow of current in the secondary of repeating coil 222 includes the receiver of the observer's telephone 221 at position F. In this manner the observer receives a signal when the regular operator collects the coin. The release of the coin collect key 33 by the regular operator permits relays 153, 155 and 157 to release, whereupon the tone to the observer ceases. In a similar manner, the observer receives a tone when the regular operator refunds a coin, as in the case where the calling subscriber does not obtain connection with a definite line called for. Coin refund key 41 is operated when the regular operator refunds the coin, whereupon relay 40 operates to light the pilot signal 37. The electromagnet 30 being energized, moves armature 31 about its pivot point to close its upper contact, and in so doing refunds the coin to this subscriber in any well-known manner. Relay 155 also operates, permitting polarized relay 156 to operate and causing the operation of relay 157. Interrupter 161, instead of 158, will thereupon be included in circuit with battery and primary of repeating coil 159. The number of segments on interrupters 158 and 161 being different, the observer receives tones of different frequencies, and is thereby enabled to determine by these different tones when the regular operator collects or refunds a coin.

In order for the observer to identify the telephone line upon which service is being observed, the indicating lamps shown in Fig. 6 are provided and mounted upon the service observing desk. The observer at some time while a telephone line is connected to the service observing trunk will actuate a key which controls the main indicating circuit. Assuming now that the observer at position F actuates key 217, signal lamp 223 will be lighted to assure this observer that she has control of the indicating circuit. It will be noted that battery is fed through series contacts of keys 217 and 218 in positions F, G, and through similar keys in other positions, if there be any provided at the service observing desk, so that only one observer can have control of the indicating circuit at a time. Actuation of key 217 also causes the operation of relay 224 and causes the intermittent operation and release of electromagnet 328, the operating circuit therefor being from a source of alternating current 327 through the primary of a transformer 329, the winding of electromagnet 328, the contact thereof and the right-hand alternate contact of key 217 to ground. Electromagnet 328, in operating, removes the short-circuit from about resistance 330, whereupon the electromagnet releases its armature, causing the short-circuit to be established again. This cycle of operating and releasing continues as long as key 317 remains actuated. The operation of relay 224 causes the operation of relay 216 over a circuit from battery 70 through the contact of relay 224, contact 225 of key 206 and the winding of relay 216 to ground. Relay 216, in operating, causes the operation of relay 202 over a circuit from battery, through the contact of relay 75 224, contact 225 of key 206, the winding of relay 202 and the upper alternate contact of relay 216 to ground. Relay 216, in operating, also causes the operation of relay 162 over a circuit which includes the secondary 80 of repeating coil 331, middle and lower alternate contacts of relay 216 and the windings of relay 162. The current in this path is current induced from the primary of repeating coil 331, which is in circuit with the 85 secondary of transformer 329 into which has been induced a high-frequency alternating current from the varying flow of alternating current through the primary of transformer 329. Relay 162 operates, opening its contact, permitting the release of relay 160. Relay 160, in releasing, closes its alternate contact, completing a circuit for relay 108, which operates. Relay 108, in operating, causes the operation of relays 90 332 and 333 over a circuit from battery, through resistance 150, contact of relay 115, middle alternate contact of relay 108, retard coil 124, ring conductor of the service observing trunk D, retard coil 209, lower 190 alternate contact of relay 202, windings of relays 332 and 333, lower alternate contact of relay 216, winding of relay 121, lower normal contact of relay 119, winding of relay 128, upper normal contact thereof and 105 alternate contact of relay 105 to ground. Relay 332, in operating, causes the operation of relays 334, 335 and 336 over a circuit from battery through the windings of these three relays and the alternate contact 110 of relay 332, to ground. The operation of relay 334 completes a circuit for lamp 301 from battery, through lamp 301, upper alternate contact of relay 334, upper normal contacts of relays 337 and 338, and 115 normal contacts of relays 339 and 340 to ground. The lighting of this lamp indicates to the service observer that the line upon which service is being observed is No. 1 of the twenty-six to which the service 120 observing trunk has access. It is to be here noted that the actual numbers of the twenty-six lines, to which the service observing trunk has access at any one time, have been associated with the numbers 1 to 26, 125 and that the service observers have lists showing this association. In this manner, when a particular indicating lamp lights, the number thereof can be immediately associated with the actual number of the line 130.

- upon which service is being observed. The release of key 217, after indicating lamp 301 has lighted, permits all apparatus, which was originally affected by the actuation of 5 this key, to return to the condition in which it was before the key was actuated. The indicating circuit is then in condition to be used by any other operator at the service observing desk.
- 10 When an observation has been completed and the observer has determined the number of the telephone line under observation, it is necessary to release the telephone line from the service observing trunk. To do 15 this, the observer operates release key 219, which connects a high voltage battery 226, preferably of 110 volts, through the contact of key 219, contact 227 of key 206, lower normal contact of relay 216, winding of relay 121, lower normal contact of relay 119, winding of relay 128, normal contact thereof and alternate contact of relay 105 to ground. Relay 128 will thereupon be operated, completing a circuit for relay 104 20 from battery, through the lower alternate contact of relay 128 and the upper winding of relay 104 to ground. The operation of relay 104 causes relays 105, 113, 114 and 115 to release, whereupon telephone line No. 1 25 will be disconnected from the service observing trunk D.
- Keys 206 and 214 at the service observing desk are preferably of the locking type, for either key must remain actuated while 30 a line connected with the trunk is under observation, and when actuated both the upper and lower movable contacts are moved to disengage the normal contacts and to engage the alternate contacts. Keys 217, 40 218, 219 and 220 at the service observing desk are preferably of a non-locking type, for these remain actuated for only a short time.
- Suppose that a call be made on telephone 45 line No. 26; the operation of line relay 42, in addition to lighting the line lamp, causes the operation of relay 101, which, in turn will cause the operation of relay 102. Relay 102 in operating, causes the operation of 50 relays 109 and 110, and the operation of the latter relay completes a circuit from relays 143 and 116, the circuit of the former being from battery, through the winding of relay 145, winding of relay 143, contact of relay 110, lower engaged contacts of the jack 142 and plug 28, and the contact of line relay 42 to ground, and the circuit of relay 116 being from battery, through winding of relay 146, the winding of relay 116, 55 contact of relay 110, engaged contacts of the jack 142 and the plug 28, and the contact of line relay 42 to ground. Relay 143, in operating, connects the limbs of telephone line #26 to tip and ring conductors 60 of the service observing trunk, and relay 65 116, in operating, completes a locking circuit for relays 143, 145, 146 and 116 over the circuits including the windings of these relays, the lower alternate contact of relay 116, the winding of relay 105, and the contact of relay 104 to ground. The operation of relay 102 also causes the operation of relay 201, which causes the lighting of lamps 204 and 205 in positions F and G of the service observing desk. The operation of 70 relay 105 causes the release of relay 102, which, in turn, releases relays 109 and 110. The release of relay 102 also removes the ground which controls the lighting of lamps 204 and 205, but the lamps remain lighted, 75 for relay 112 operates immediately after the operation of relay 116 and furnishes a ground in place of that removed by the release of relay 102. Assuming that the observer at position G has noticed the lighted 80 condition of lamp 205, she actuates key 214, causing lamps 204 and 205 to be extinguished and lamp 228 to be lighted. The observer's telephone 229 will also be connected to tip and ring conductors of the 85 service observing trunk. The regular operator, noticing the lighted condition of the line lamp, now answers in the usual manner by inserting the answering plug into the jack associated with telephone line No. 26, 90 whereupon the cut-off relay 43 and relay 117 will be operated. Relay 118 does not operate at this time. The operation of relay 117 causes the operation of relays 119, 120 and 122. The operation of relay 122 95 connects battery to the voltmeter relay 126. Since telephone line No. 26 is a message register line, the fourth arm of the Wheatstone bridge of the voltmeter relay will be made up of the winding of the cut-off relay 100 and the winding of the electromagnet of message register 32 in parallel, the windings of relays 117 and 118 in series and 105 resistance 130 connected in parallel. It is to be noted that this fourth arm of the 110 bridge, in the case of a telephone line equipped with a message register, contains the winding of the electromagnet of the message register, whereas in the case of a line not equipped with a message register, 115 this winding is replaced by resistance 129.
- When the subscriber on telephone line No. 26 has been connected with a called telephone line, the regular operator registers the call on message register 32 by the actuation of key 110 35. This is accomplished by establishing the following circuit upon the actuation of key 35 from battery 44, preferably of 36 volts, through the winding of the electromagnet of a position register 45, contact 46 of 120 key 35, sleeve contacts of answering plug and jack, both windings of electromagnet 32, of the line register to ground. The electromagnets of both the line register 32 and 125 position register 45 are energized, attracting 130

their armatures to cause the registration of the call. When the armature of electromagnet 32 is attracted, the righthand winding thereof is short-circuited, whereupon this magnet will remain energized from the regular central office battery after the release of key 35. When the electromagnet of the position register 45 and the electromagnet 32 of the line register were energized, relay 118 was operated over a circuit from battery 44 through the winding of the electromagnet of position register 45, contact 46 of key 35, sleeve contacts of the answering plug and jack, upper engaged contacts of the plug 28 and jack 142, middle contact of relay 116, and windings of relays 117 and 118 to ground. Relay 118 is responsive to a flow of current from a 36 volt battery, but is not responsive to flow of current from the regular central office battery of 24 volts. Relay 118 in operating, causes the operation of relay 230 over a circuit from battery through the winding of relay 230, middle normal contact of relay 216, retard coil 231, lower normal contact of relay 108 and contact of relay 118 to ground. Relay 230 in operating, lights lamp 232 and operates buzzer 233, the circuit therefor being from battery through the contact of relay 230, contact 234 of key 214, lamp 232 and buzzer 233 and contact thereof in parallel to ground. The lighting of the lamp and the operation of the buzzer indicate to the observer that the regular operator has registered a call on the telephone line which is connected to the service observing trunk. The release of key 33 by the regular operator releases relays 118 and 230, whereupon lamp 232 is extinguished and buzzer 233 ceases to operate. The voltmeter relay 126 operates in the same manner as hereinbefore described in connection with a call on telephone line No. 1 to control the signal lamp 235 instead of 207 for indicating the position of the subscriber's switchhook to the observer. Signal lamp 235 was operated when the regular operator plugged in to answer the call on telephone line #26 to indicate this fact to the observer. The signal lamp 236 and buzzer 237 are for the purpose of indicating to the operator in position F when the regular operator registers on a line, that is, should the observer in position F be observing the service on a line with which is associated a line register. To get an indication of the number of the line upon which service is being observed, operator G actuates key 218, which causes the operation of relays 238, 202, 216, 162, the release of the relay 160 and the operation of relay 108. The operation of these relays causes the operation of relays 339, 340, 341, 342 and 333. The energizing circuit for relays 339 and 340 is from battery through resistance 165, lower contact of relay 143, lower alternate contact of relay 108, retard coil 231, middle alternate contact of relay 216, windings of relays 340 and 339, lower alternate contact of relay 216, winding of relay 121, lower normal contact of relay 119, winding of relay 128, normal contact thereof and alternate contact of relay 105 to ground. The circuit for relays 341 and 342 is from battery through resistance 148, contact of relay 145, upper alternate contact of relay 108, retard coil 106, tip conductor of the service observing trunk, retard coil 203, upper alternate contact of relay 202, windings of relays 341 and 342, lower alternate contact of relay 216, winding of relay 121, lower normal contact of relay 119, winding of relay 128, normal contact thereof and alternate contact of relay 105 to ground. Relay 333 operates over a circuit from battery through resistances 150 and 149, contact of relay 146, middle alternate contact of relay 108, retard coil 124, ring conductor of the service observing trunk, retard coil 209, lower alternate contact of relay 202, windings of relays 332 and 333, lower alternate contact of relay 216, winding of relay 121, lower normal contact of relay 119, winding of relay 128, normal contact thereof and alternate contact of relay 105 to ground. Relay 332 is marginal and does not operate when in circuit with resistances 149 and 150, but does operate when resistance 149 is not in the circuit, as was the case when the service observing trunk was connected to telephone line No. 1. The operation of relay 341 causes the operation of relay 338. The operation of relay 333 causes the operation of relays 343, 344 and 345. Indicating lamp 326 is now lighted over a circuit from battery through lamp 326, lower alternate contact of relay 105, 345, lower normal contact of relay 336, lower alternate contact of relay 338 and alternate contact of relay 340 to ground. The observer at position G receives an indication, by means of the lighted condition of lamp 326, of the number of the line upon which service is being observed. Release of the indicating controlling circuit key 218 permits all apparatus associated with the indicating circuit to assume its normal condition. The telephone line #26, upon which service is being observed, may be released by the actuation of release key 220 by the observer at position G, the apparatus functioning in precisely the same manner as described in connection with the release of telephone line #1. It is to be noted that relays 339 and 340 are always in series, the same being true of relays 341 and 342, and relays 332 and 333. Relays 339, 342 and 333 always operate when a circuit is completed through their windings. Relays 340, 341 and 332 are marginal and do not operate when either resistances 147 and 148, or 149 and 150, or 165 and 166

are included in circuit with the winding of any of these relays. Any one of them will, however, operate, if neither resistance 147 nor 149 nor 166 is in the circuit. Resistances 147, 149 and 166 are high, each being preferably of about 15,000 ohms, while resistances 148, 150 and 165 are low, each being preferably of about 200 ohms. The manner of connecting resistances 147, 148, 149, 150, 165 and 166 in circuit with relays 339, 340, 341, 242, 332, and 333 depends entirely upon the manner in which the leads A, B and C, for the two relays individual to a telephone line, are connected to the leads 1 to 7 inclusive. From the table in Fig. 4, it will be evident that the manner of connecting these leads is different for each line. It will be clear, therefore, without further description, that upon the actuation of either key 219 or 220 in positions F or G of the service observing desk, the proper indicating lamp will be lighted to indicate to the observer the number of the telephone line upon which service is being observed.

25. What is claimed is:

1. In a service observing system, a trunk circuit extending from a central office to a service observing desk, a plurality of telephone lines terminating at the central office, means associated with the trunk circuit for automatically connecting a calling telephone line with the trunk circuit, a signaling device at the service observing desk for each of the telephone lines, apparatus comprising marginal relays adapted to coöperate to cause the operation of the signaling device corresponding to the telephone line connected to the trunk circuit to indicate the number of the connected telephone line, and means controlled by the observer for causing said apparatus to coöperate.
2. In a service observing system, a trunk circuit extending from a central office to a service observing desk, a plurality of telephone lines terminating at the central office, a plurality of resistances at the central office, means associated with the trunk circuit for connecting a calling telephone line with the trunk circuit and for selecting one or more of the resistances, a source of current, a signaling device at the service observing desk for each of the telephone lines, apparatus comprising marginal relays adapted to coöperate to cause the operation 55 of the signaling device corresponding to the telephone line connected to the trunk cir-

cuit to indicate the number of the connected telephone line, a key at the service observing desk, and a relay operating upon the actuation of the key to include the source of current, the selected resistance or resistances and said apparatus in circuit to cause the coöperation of said apparatus.

3. In a service observing system, a trunk circuit extending from a central office to a service observing desk, a plurality of telephone lines terminating at the central office, a plurality of resistances at the central office, means associated with the trunk circuit for connecting a calling telephone line with the trunk circuit and for selecting one or more of the resistances, a source of current, a signaling device at the service observing desk for each of the telephone lines, apparatus comprising three sets of relays, one of each set being marginal, adapted to coöperate to cause the operation of the signaling device corresponding to the telephone line connected to the trunk circuit to indicate the number of the connected telephone line, a key at the service observing desk, and a relay operating upon the actuation of the key to include the source of current, the selected resistance or resistances and one or more sets of said relays in circuit to cause the coöperation thereof.

4. In a service observing system, a trunk circuit extending from a central office to a service observing desk, a plurality of telephone lines terminating at the central office, a plurality of high and low resistances, means associated with the trunk circuit for connecting a calling telephone line with the trunk circuit and for selecting one or more of the resistances, a source of current, a signaling device at the service observing desk for each of the telephone lines, a plurality of relays adapted to coöperate to cause the operation of the signaling device corresponding to the telephone line connected to the trunk circuit to indicate the number of the connected telephone line, and a relay operating under control of the observer to cause the operative association of the source of current, the selected resistance or resistances and said relays, whereby the signaling device corresponding to the connected telephone line is operated.

In witness whereof, I hereunto subscribe my name this 24th day of November, A. D. 1915.

HARRY L. DARRAH.
